UNITED STATES PATENT OFFICE.

JOHN H. MILLER, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

KNIFE-SWITCH.

No. 921,434.

Specification of Letters Patent.

Patented May 11, 1909.

Application filed October 14, 1907. Serial No. 397,286.

To all whom it may concern:

Be it known that I, JOHN H. MILLER, a citizen of the United States of America, residing at Bridgeport, in the county of Fairfield and 5 State of Connecticut, have invented certain new and useful Improvements in Knife-Switches, of which the following is a specification.

My invention relates more particularly to 10 the construction of the joint between the block and the blades of the posts of the switch and has as its object a strong as well as a simplified construction of improved appearance.

15 In the accompanying drawings Figure 1 is a side elevation of a switch with posts having my improved construction; Fig. 2 is a perspective of a post with, one of the blades detached; Fig. 3 is a plan of a block; Fig. 4 is a 20 perspective of a post upside down; and Fig. 5 is a section on the line *a—a*, Fig. 1.

In the construction of knife switch posts having comparatively thin base blocks, it is customary to secure the posts to the block by 25 slitting the end of the latter, inserting the blades which form the post and then "sweating" the parts together. It is impossible on account of the thinness of the block to drill the same and run securing pins through as is 30 customary with heavy blocks, so that the manufacturer is at the mercy of the soldered joint above described, which is quite apt to break when the hole is drilled and tapped for the screw. Furthermore the split end of the 35 block with the blades of the post showing, detracts from the appearance of the finished article. A more satisfactory post not only in appearance, but also in strength and durability is made by punching slots 12 in one 40 end of the base leaving a tie strip 13 at the end uniting the strips. The blades or preferably tongues 14 on the blades may be inserted in the slots and the parts sweated together as readily as if the end were slit as 45 customary. At the same time I propose to

punch the hole 15 for the securing screw 16. In connection with this I form out or groove the lower ends of the blades to form bowed offsets 17 which conform to the contour of the hole 15. Thus after the parts have been 50 "sweated" together the tap may be carried up into the grooved portion 17 of the blades, so that the securing screw is given purchase on the blades as well as on the base. This adds rigidity to the structure. It will be 55 noted also that apart from the effect of the securing screw, the grooved portion acts as a lateral supporting rib at the base of the blades and gives further stability to the structure as well as presenting a very neat 60 appearance.

I claim as my invention:

1. In a switch terminal for knife switches, blades comprising the post having bowed offsets at their lower ends, in combination with 65 a base having a hole punched from the body thereof to receive the ends of said blades and form with said bowed offsets thereon a recess adapted to receive a securing means, said hole being spaced from the end of the base to 70 leave a tie strip, substantially as described.

2. In a switch post for knife switches, blade posts provided with downwardly extending tongues and bowed offsets at their lower ends, in combination with a base having 75 a hole punched from the body thereof to receive said tongues and form with said bowed offsets a recess adapted to be threaded to receive a securing screw, said hole being so spaced from the end of the base that the 80 edges of the blades come substantially flush with the said end, substantially as described.

In testimony whereof I have signed my name to this specification, in the presence of two subscribing witnesses.

JOHN H. MILLER.
